ATTORNEY

UNITED STATES PATENT OFFICE

HENRY C. MAUL, OF DETROIT, MICHIGAN, ASSIGNOR TO DETROIT-MICHIGAN STOVE COMPANY, OF DETROIT, MICHIGAN, A CORPORATION OF MICHIGAN

DESIGN FOR A GAS STOVE

Application filed February 16, 1931. Serial No. 38,683. Term of patent 14 years.

To all whom it may concern:

Be it known that HENRY C. MAUL, a citizen of the United States, residing at Detroit, county of Wayne, State of Michigan, has invented a new, original, and ornamental Design for Gas Stoves, of which the following is a specification, reference being had to the accompanying drawings, forming part thereof.

Fig. 1 shows a stove with a folding cover in burner concealing position, showing my new design.

Fig. 2 shows the same in burner exposing position, the covering being folded back.

The dominant features of the design reside in (a) the heavy, table-like, frame or base upon which the stove proper rests; (b) the table-like top for the oven compartment; (c) the table-like burner top; and (d) the permanent splasher plate which gives the stove the same appearance whether the folding top be up or down.

I claim:

The ornamental design for a gas stove, substantially as shown and described.

In testimony whereof, I sign this specification.

HENRY C. MAUL.
